Primary Examiner — Kendra Leslie Hamilton*Assistant Examiner* — Michael Hoffman(74) *Attorney, Agent, or Firm* — Woodard, Emhardt, Henry, Reeves & Wagner, LLP(57) **CLAIM**

The ornamental design for a test strip reference board as shown and described.

DESCRIPTION

FIG. 1 is a front, plan view of the test strip reference board showing my new design.

FIG. 2 is a plan view of the back thereof;

FIG. 3 is a perspective view of the rear, the bottom edge, and the left side edge thereof;

FIG. 4 is a bottom, elevational view thereof;

FIG. 5 is a top, elevational view thereof; and,

FIG. 6 is a left side, elevational view thereof. The right side, elevational view is a mirror image of the left side view. The broken lines in FIGS. 2 and 3 show portions of the article forming no part of the claimed design. The drawings are not lined to indicate particular colors.
